UNITED STATES PATENT OFFICE.

HARRY A. CUMFER, OF CHICAGO, ILLINOIS, ASSIGNOR OF ONE-HALF TO THE FLINT-KOTE COMPANY, OF BOSTON, MASSACHUSETTS, A CORPORATION OF MASSACHUSETTS.

ROOFING ELEMENT.

Application filed October 2, 1924. Serial No. 741,115.

This invention relates to improvements in roofing elements and product thereof, and refers more particularly to the production of roofing strips or slabs having incisions 5 adjacent one longitudinal edge, the incised portions being folded back upon the body portion of the slab or strip to present a longitudinal edge having a plurality of notches taking more or less of a frusto-triangular 10 form. The process of slitting consists essentially in feeding a strip of previously prepared roofing felt saturated with a waterproofing compound and having a granular surfacing on one surface thereof, through 15 any suitable apparatus. The sheet is severed transversely to produce individual roofing strips and is preferably simultaneously slit in the form of short opposed converging diagonal lines, terminating short of an 20 actual meeting. These diagonal lines are preferably formed on one side only of the transverse line of severance as the sheet is fed forward, in order that the portions between the slits may be folded back upon the 25 main body of the strip as part of a continuous operation. There may be any number of slits but I show eight slits to form four tabs and corresponding notches.

Some of the advantages of my invention 30 are the utilization of the entire strip and the prevention of any waste in cutting to produce self-spacing shingle strips and the ornamental effect produced when laid on a roof.

35 In the drawings:

Fig. 1 is a plan view of a roofing sheet showing the transverse and diagonal lines of severance.

Fig. 2 is a plan view of an individual 40 strip.

Fig. 3 is a plan of a roof laid with the individual slabs in position, the base of succeeding strips abutting the upper edge of the turned back tab.

45 Fig. 4 is an enlarged perspective view of the edge of an individual slab showing the notch and corresponding tab imposed on the body of the strip.

Fig. 5 is a view similar to Fig. 3 with the 50 base of succeeding strips supported in a pocket formed by the turned back tabs.

Fig. 6 is a cross sectional view taken on lines 6-6 of Fig. 5.

55 Referring in detail to the drawing, 1 designates a strip of roofing felt which has

been previously impregnated with a waterproofing material such as asphalt, one or both surfaces of which may have imposed thereon a granular surfacing. This strip may be any length, for instance, may be fed 60 from a roll and is transversely severed as shown at 2, the sheet being fed forward in the direction shown by the arrow.

Communicating with the transverse severing line 2, the strip is slit to provide a 65 plurality of sets of converging diagonal incisions 3, the extremities of which terminate short of an actual meeting to provide uncut portions 4, for a purpose hereinafter explained.

The roofing sheet 1 is fed through any suitable form of machine which will sever the sheet as shown in Fig. 1, and equipped with means for folding back the tabs 5 upon the surface of the body of the individual 75 slab or strip, the uncut portion 4 being the connecting means. The tab 5 may have its entire area attached to the body of the strip by any suitable adhesive as shown in Figs. 3 and 4, or a portion of the tab 5 may be 80 attached, leaving the upper end unattached to form a pocket 6 as shown in Figs. 5 and 6.

In the form shown in Figs. 3 and 4, the upper edge 7 of the tab 5 forms a butt 85 against which the base 8 of the overlying shingle is adapted to be placed. It will thus be seen that by my invention, all of the original roofing material is utilized without any waste and at the same time producing 90 individual self-spacing shingles.

In the form shown in Figs. 5 and 6, the upper edge 7 of the tabs 5 are unattached to the body of the roofing sheet to form pockets 6 in which the base 8 of the overlying 95 shingles is adapted to be inserted and locked fixedly in position.

The result, when laid upon a roof, is an attractive design, in which the tabs 5 preferably display a color different from the color of the granular surfacing on the upper surface of the main body portion. These tabs 5 when folded back may present a black surface which is preferably not coated with a granular surfacing, while the granular surfaced side may be green, gray, red or any 100 color.

The details of the construction may be varied, without departing from the scope of my invention, except as set forth in the appended claims.

I claim as my invention:

1. A self-spacing roofing strip provided adjacent one longitudinal edge with sets of opposed converging, tapering incisions, terminating short of meeting to form intermediate tabs between the opposed incisions, said tabs being folded upon and attached to the body portion of the strip.
2. A self-spacing shingle strip adapted for use with others, comprising a waterproofed felt having a granular surfacing

and having along one longitudinal edge a plurality of sets of diagonal incisions, the individual incisions of each set converging but terminating short of meeting, the portions between each set of incisions being folded back upon and attached to the body portion of the strip to form self-spacing butts for overlying shingles, and semi-hexagonal notches extending inwardly from one ¹⁵ ~~20~~ edge.

HARRY A. CUMFER.
